DESIGN FOR A TOY BANK OR SIMILAR ARTICLE

Joseph Burgess Lenhart, Marietta, Ohio

Application February 14, 1945, Serial No. 117,934

Term of patent 14 years

(Cl. D34—11)

To all whom it may concern:

Be it known that I, Joseph Burgess Lenhart, a citizen of the United States of America, residing in Marietta, county of Washington, and State of Ohio, have invented a new, original, and ornamental Design for a Toy Bank or Similar Article, of which the following is a specification, reference being had to the accompanying drawing, forming part thereof, wherein,

I claim:

The ornamental design for a toy bank or similar article, substantially as shown.

JOSEPH BURGESS LENHART.
